(57) **CLAIM**

I claim the ornamental design for an audio system remote control, as shown and described.

DESCRIPTION

FIG. 1 is a front perspective view of an audio system remote control showing my new design;

FIG. 2 is a left-side view thereof;

FIG. 3 is a right-side view thereof;

FIG. 4 is a front view thereof with keypad extended;

FIG. 5 is a rear view thereof;

FIG. 6 is a bottom view thereof;

FIG. 7 is a top view thereof; and,

FIG. 8 is a front view thereof with keypad retracted.

The broken lines in the figures depict portions of the control that form no part of the claimed design.
